United States Patent Office

Des. 230,384
Patented Feb. 19, 1974

230,384

COUCH

Richard Alan Bialosky, 257 Cloydon Circle,
Santa Barbara, Calif. 93108

Filed Apr. 12, 1972, Ser. No. 243,552

Term of patent 3½ years

Int. Cl. D6—01

U.S. Cl. D6—61

FIG. 1 is a front elevation view of a couch, showing my new design.

FIG. 2 is a side elevation view.

FIG. 3 is a back elevation view, and

FIG. 4 is a perspective view.

I claim:

The ornamental design for a couch, as shown.
